REGULATING APPARATUS

Morton O. Snediker, Chicago, Ill., assignor to The Powers Regulator Company, Chicago, Ill., a corporation of Illinois

Original No. 1,530,917, dated March 24, 1925, Serial No. 626,246, March 19, 1923. Application for reissue August 16, 1934, Serial No. 740,147

7 Claims. (Cl. 236—44)

My invention relates to thermostatic regulation and particularly to novel means adapted for employment in the controlling of relative humidity in rooms.

5 One of the objects of my invention is to improve the means employed for maintaining relative humidity and to adapt such means for use in rooms in which operations are carried on requiring the maintenance of certain specified air 10 conditions.

It is, of course, well known that slight variations in the dry air temperature necessitates relatively greater variations in the moisture content of the air in order to maintain a constant relative humidity. In the carrying out of certain operations, particularly in the treatment of silk, cotton, etc. it is necessary to maintain a predetermined relative humidity, notwithstanding an increase in out-door temperature to a point above 15 the predetermined normal for the room. This improvement has to do with means influenced by changes in the dry air temperature for immediately changing the moisture content of the air delivered to the desired space. The mechanism 20 includes, as the principal element in the combination, a pair of thermostats, one influenced by the dry air temperature, the other influenced and serving to maintain constant the temperature of a supply of water for delivery with the 25 incoming air, the dry air thermostat serving to modify the action of the liquid control thermostat. As a result of the use of this apparatus 30 a slight change in the dry air temperature effects a material change in the temperature of the water supplied to the space under control; consequently the amount of moisture taken up, due 35 to a variation in the degree of vaporization, is varied to a degree sufficient to maintain constant the relative humidity.

40 The invention will be more readily understood by reference to the accompanying drawings, wherein:

Fig. 1 is a view partly diagrammatic in form, illustrating the application of apparatus such as 45 contemplated;

Fig. 2 is a longitudinal sectional view through one of the regulators employed; and

Fig. 3 is a similar view through the other thermostatic regulator.

50 Referring particularly to Fig. 1, it will be seen that the apparatus is shown installed in connection with walls providing a room 10 adapted to be heated by steam coils 11, air being blown into the room over the coils by means of the motor driven fan 12. A steam valve 13 is controlled by

means of a thermostat 14 mounted within the room. The thermostat may be of the type shown in Fig. 3, the construction and operation of which are well known in the art but which for convenience will be briefly described.

5 The thermostat comprises a casing 15, having a compressed air inlet passage 16 and an outlet passage 17. A pipe 18 is connected with a suitable source of air supply while the pipe 19 is connected to the valve 13. Mounted in the casing 15 is a bellows 20 containing a thermosensitive liquid, one wall of the bellows being rigidly connected to an arm 21, the lower end of which is supported on an adjusting bolt 22. At an intermediate point a second adjusting element 23 acts as a fulcrum and provides for the fine adjustment as required.

10 The other wall of the bellows is connected through a member 24 to a flexible diaphragm 25 secured to the casing. The member 24 provides a 20 valve seat 26 and an exhaust port 27. A valve 28 cooperates with the valve seat 26 and is located in a chamber 29 in the casing 15 and in communication with the outlet passage 17. The passages 16—17 are placed in and out of communication 25 by means of a valve 30, contacting the valve 28 and normally held in seated position by means of a spring 31. In the position of the parts shown in Fig. 3, the steam supply valve would be in a static condition. However, upon an increase in 30 temperature in the room the bellows would be expanded and the motion thereof would serve to open the valve 30, permitting air pressure to pass into the pipe 19 to the valve 13 and to close the same. As the temperature drops due to the 35 shutting off of the steam, the first action due to contraction of the thermostatic element is the closing of the valve 30. Further contraction of the bellows due to the movement of the valve 28 out of contact with the valve 30 is the opening of 40 the valve 28 permitting escape of the air pressure through the port 27, and the opening of the steam valve 13.

45 This provides for the control of the dry air temperature within the room 10. However, in order to control the relative humidity, means such as the spray 32 are provided, water being supplied through the pipe 33 and steam for modifying the temperature of the water through the pipe 34. A thermostatic element 35 is inserted in the spray 50 pipe and the action of this thermostat controls the supply of steam through the valve 36. The thermostat for effecting this operation is illustrated in detail in Fig. 2.

55 For convenience the thermostatic element com-

prises two materials of different degrees of expansibility under heat, the inner element 37 which is relatively movable carrying a valve seat 38 in communication with a coil 39 of flexible pipe located 5 within a chamber 40 which is in constant communication with a source of maintained air pressure through a pipe 41. The coil of pipe 39 is in communication with an outlet pipe 42 connected to the steam valve 36, and expansion spring 38^a 10 tends to unseat the valve member 52.

In the thermostat just described, an increase in temperature of the water supply results in a movement of the thermostatic element 37 and a partial opening of the valve 52. This permits the escape 15 of air from the chamber 40 through the coil of the pipe 39, into the pipe 42 which effects the partial closing of the steam valve 36. In order to prevent too abrupt movement of the steam valve and to assist in maintaining a balanced condition as 20 required, I provide a constantly open air escape port 43 controlled by a set screw 44, by means of which the area of the escape opening is limited to the desired extent.

In the event that the dry air temperature in the 25 room were maintained absolutely constant, a predetermined temperature of water to the spray could be maintained and the relative humidity would therefore be constant. However, variations in the dry air temperature due to excessive 30 out-door temperatures cannot be avoided and in order to maintain the desired constant relative humidity it is necessary to materially change the temperature of the spray water immediately following changes in the dry air temperature. To 35 that end I provide means for modifying the action of the water control thermostat by the air thermostat. This means comprises a second thermostat 14 which is a duplicate of that shown in Fig. 3 and which might, except for practical considerations, 40 be accomplished by the use of one instrument instead of the two shown in Fig. 1. However, the second thermostat 14, shown in Fig. 1, has the same air supply pipe 18 and an air discharge pipe 45 which communicates with the bellows 46 shown 45 in Fig. 2. One wall of the bellows is fixed in a frame 47 rigidly held, while the other wall carries a threaded plunger 48 which may have an adjusting finger 49 secured thereto. The plunger rests 50 against the movable wall 50 of a sealing-bellows and contacts a stem 51 which bears at its inner 55 end against a valve 52 which controls the port 38. It will be seen that upon an increase in dry air temperature in the room the air pressure permitted by the thermostat to enter the pipe 45 will be exerted in the bellows 46 and the force thereof transmitted to the stem 51 tending to more firmly seat the valve 52. Therefore a much greater increase in water temperature must occur before sufficient elongation of the thermostatic element 60 will take place to open the valve 52 and effect the shutting off of the steam valve 36. Thus upon an increase of temperature in the room the water temperature in the spray is materially increased, and although the temperature of the heating coils 65 will be immediately reduced due to the action of the dry air thermostat the higher water temperature will enable the taking up of a greater amount of water and serve to maintain the relative humidity.

70 No attempt is made herein to claim the system of maintaining the relative humidity. The appended claims are directed to the apparatus by which the adjustment of one thermostat is changed by the action of a second thermostat influenced by a different medium. As stated in

the preceding paragraph, a change in the dry air temperature reflected by the first thermostat will, under the conditions stated, result in a material increase in the water temperature as controlled by the second thermostat—in other words, for 5 each degree of change in the dry air temperature there will be several degrees increase in the water temperature. This is brought about by controlling the adjustment of the second thermostat and it is obvious that this ratio may be changed as 10 required. It is also obvious that by a reversal of the parts, the opposite action may take place—that is, if the situation should call for a reverse operation, the second thermostat could be arranged to provide for a reduced instead of an increased temperature of the medium controlled thereby, following an increase in temperature of the medium in which the first thermostat is located.

I claim:

1. In regulating apparatus, the combination of a thermostat having its thermo-sensitive element located in a medium whose temperature is to be controlled, a valve for controlling the supply of heat to said medium, means for supplying fluid 25 under pressure to said valve, a thermostatic valve operable by said thermostat for controlling the action of said fluid under pressure on said heat controlling valve, a second thermostat, and means operable thereby for changing the position of said 30 thermostatic valve relative to said first thermostat.

2. In regulating apparatus, the combination of a thermostat having its thermo-sensitive element located in a medium whose temperature is to be 35 controlled, a valve for controlling the supply of heat to said medium, means for supplying fluid under pressure to said valve, a thermostatic valve operable by said thermostat for controlling the action of said fluid under pressure on said heat 40 controlling valve, a second thermostat distantly located and having its thermo-sensitive element in a different medium than that in which said first thermostat is located, and means operable by 45 said second thermostat for changing the position of said thermostatic valve relative to said first thermostat.

3. In means of the class described, the combination of a thermostat adapted to be interposed in a conduit for a body of fluid, means for supplying heat to said body of fluid, a valve affected by the movement of said thermostat, said valve controlling the supply of heat to said body of fluid, a plunger abutting said valve, a diaphragm bellows, a movable portion of which is in contact 55 with said plunger, and a second, distantly-located thermostat acting on said diaphragm bellows to position said plunger in its relation to said valve.

4. In a device of the class described, the combination of a thermostatic element, a valve movable relative thereto and controlling the supply of heat to a space, a plunger abutting said valve, a diaphragm bellows, a movable wall of which abuts said plunger, and a second, distantly-located thermostat acting on said bellows to position said 60 plunger and thereby to change the adjustment of said first thermostatic element.

5. In a device of the class described, the combination of a casing having an inlet and an outlet for fluid under pressure, a thermostatic element 70 movable relative to said casing, a valve cooperating with and movable relative to said element, a flexible tube providing communication between said element at one side of said valve and the outlet from said casing, valve-operating means in- 75

dependent of said thermostatic element, a second, distantly-located thermostat which is thermally responsive to an independent heat condition, and means operable by said second thermostat for 5 positioning said valve-operating means.

6. In regulating apparatus, the combination of a thermostat having a movable thermostatic element, a valve primarily controlled by the movement of said element, said valve serving to regulate a supply of heat to a space, a secondary control for said valve, consisting of means acting in 10 opposition to said thermostatic element, a second, distantly-located thermostat, and a diaphragm

bellows actuated by said second thermostat for moving said secondary valve-control means.

7. In a thermostatic device, the combination of a thermostatic element, a valve associated therewith and adapted to control a supply of heat, a plunger acting on said valve in opposition to said thermostatic control, manually operable means for positioning said plunger, a diaphragm bellows acting through said manually operable means to vary the position of said plunger, and 10 a second, distantly-located thermostatic element for actuating said diaphragm bellows.
